[57] CLAIM

The ornamental design for a golf ball and tee setter, as shown and described.

DESCRIPTION

FIG. 1 is a perspective view of a golf ball and tee setter showing my new design;

FIG. 2 is an enlarged front elevational view thereof;

FIG. 3 is an enlarged right side elevation view, the left side being a mirror image thereof;

FIG. 4 is an enlarged rear elevation view thereof;

FIG. 5 is an enlarged top view thereof; and,

FIG. 6 is an enlarged bottom view thereof.

The broken line showing of the golf ball and the tee shown in FIG. 3 is for illustrative purposes only and forms no part of the claimed design.

The shaft is shown fragmented in FIGS. 2-4 for ease of illustration.
